UNITED STATES PATENT OFFICE.

WILLIAM H. NIEMEYER, OF BALTIMORE, MARYLAND.

EXCELSIOR-CUTTING MACHINE.

No. 823,432.

Specification of Letters Patent.

Patented June 12, 1906.

Application filed September 6, 1904. Serial No. 223,513.

To all whom it may concern:

Be it known that I, WILLIAM H. NIEMEYER, a citizen of the United States, residing at Baltimore, in the State of Maryland, 5 have invented new and useful Improvements in Excelsior-Cutting Machines, of which the following is a specification.

This invention relates to machines for making excelsior; and the object is to increase the 10 capacity of machines of this class and at the same time provide a machine of exceedingly simple construction which will be smooth and easy in its running.

The invention contemplates the arrangement 15 of the scorers and cutters on independent carriers so disposed and operated as to coöperate in the scoring of the block of wood from which the excelsior is to be formed and the cutting of the shavings therefrom.

20 The invention also contemplates the provision of simple and effective feed mechanism for feeding a series of blocks to be successively acted upon by the scorers and cutters.

With the above object in view the invention 25 consists in the novel features of construction hereinafter fully described, particularly pointed out in the claims, and clearly illustrated by the accompanying drawings, in which—

30 Figure 1 is a side elevation of a machine constructed in accordance with my invention; Fig. 2, a top plan view of the same, the disk or carrier for the cutter being broken away on one side of its center to show one a set of scorers in operative position; Fig. 3, a front elevation of the machine; Fig. 4, a transverse sectional view taken on the line 4 4 of Fig. 1; Fig. 5, a front elevation with the feed mechanism removed, showing the carrier-disk and two sets of scorers in operative 45 position relative thereto; Fig. 6, a rear elevation of the machine, partly in section to show the arrangement of the carrier for the scorers; Figs. 7 and 8, enlarged detail views showing the 50 arrangement of the scorer-heads and track upon which they travel; Fig. 9, a sectional detail view showing the manner of attaching the cutters to the carrier-disk; and Fig. 10, an enlarged detail view of the pushers of the feed mechanism, showing their construction and manner of attachment to the carrier-chains.

55 Referring now more particularly to the drawings, 1 designates the base of the machine, having raised therefrom two alined stands or bearing-supports 2, carrying suit-

able bearings for a longitudinally-extending power-shaft 3, upon the inner end of which the carrier for the cutters is attached, said carrier in the present instance being illustrated 6c as a disk 5. Said disk is formed about its face with a number of equidistant openings 6 of a size and shape to coöperate with the scorers which project therethrough to effect the scoring of the block, as will be fully described hereinafter. I have shown the disk as provided with three of these openings; but the number can be varied without affecting my invention. Formed about the base of the disk between the openings 6 are a number of radially-disposed slots 7, each of which is enlarged upon the rear side of the disk and provided with an inclined wall, to which a cutter 8 is adjustably secured, the cutting edge of which projects through the slot to the 65 front face of the disk a sufficient distance to slice a shaving of the desired thickness from the block. The number of these slots and cutters may also be varied without departing from the scope of my invention. 70

The stand or support 2 nearest the rear face of the disk carries two laterally-disposed substantially U-shaped supports 9, the arms of each of which are provided with horizontally-aligned bearings for a shaft 10, extending transversely of the machine. Each of these shafts carries on its inner end a bevel-gear 11, meshing with a similar gear 12 on a short shaft 13, mounted in a suitable bearing upon said stand 2, said shaft being driven by 75 a belt 13 from the power-shaft 3. Each shaft 10 also carries sprockets or chain-wheels 14, spaced from each other and disposed within the arms of the supports 9. Sprocket-chains 15 pass around these wheels and around 80 sprocket-wheels 16, carried by shafts 17, mounted in the supports 9 below the shafts 10, and constitute the carriers for the scorers. Attached to or formed as a link of each pair of chains is a scorer-head consisting of a 85 socket portion or bar 18, disposed between the chains of each pair, and in which a plurality of scoring teeth or knives 19 are removably secured. Each scorer-head also carries rollers 20, which travel upon the outer sides 95 of tracks 21, arranged adjacent to each chain. Extending inwardly from each scorer-head is an arm or bracket 22, in which a yielding member 23 is supported, carrying a roller 24, traveling upon the inner side of the track 21. 100 These rollers 24 are normally held against the track by the action of coiled springs 25 on

said members 23. The bearings for shafts 10 are made adjustable by any well-known structure, as illustrated, whereby the slack may be removed from the carrier-chains.

5 The operation of my invention as thus far described is as follows: The revolution of the disk is so timed with respect to the movement of the scorers that when one of the sets of scoring-teeth passes over the upper sprockets one of the openings 6 of the disk will be in such a position that the said scoring-teeth will swing thereinto and project therefrom to the front face of the disk, in operative position, to act upon the face of the block of wood which is fed to proper position by the feed mechanism presently to be described. This position of the scorer with respect to the disk will be maintained until the face of the block has been traversed, when the scorer 15 having reached the extent of its movement in a straight line will, by reason of the passage thereof around the lower sprockets, swing out of the opening 6 in the disk and begin its return movement. The tracks prevent the sagging of chains and cause the scorer to firmly engage the block, thus insuring a cut of uniform depth. The scorer having acted upon the block, the cutters following it slice shavings therefrom, said cutters being set to 20 project one slightly beyond the other, so as to cut several shavings, the combined cut of the cutters of course not exceeding the cut of the scorers. It will be understood that the scoring mechanisms, which, as illustrated, are disposed on opposite sides of the center of the carrier-disk, will travel in reverse directions, so that the scorers of one will when the machine is arranged vertically operate on the block from top to bottom thereof, while 25 the scorers of the other will move across the face of the block from bottom to top, this being necessary, as they must move in the same direction as the cutters carried by the disk. I will now describe my feed mechanism, of 30 which there are two, one on each side of the vertical center of the disk, to feed the blocks to the scoring and shaving or slicing position. Raised from the forward portion of the base 1 of the machine is a support 24', provided with horizontal longitudinally-extending dovetailed tracks 25', disposed one on 35 each side of the vertical center of the carrier-disk and at the front face thereof. Arranged to have a sliding movement on each of said tracks are two feed-boxes 26 and 27, positioned in line with each other and open at their top and ends. These boxes are separated slightly, so that the forward one may have a slight rearward movement independent of the rear box.

40 Mounted upon the exterior of each box 27, adjacent to the respective ends thereof, in suitable bearings are shafts 28, carrying spaced sprocket or chain wheels 29 for the

carrier-chains 30, which pass therearound, 45 said chains passing through suitable openings in the side walls of said boxes and extending along the inner faces of the latter. Connecting the chains of each vertical pair are pushers 31, each being pivotally attached 50 to the chains, which constitute the carrier therefor. Said pushers are provided adjacent to each end with a laterally-extending arm 32, carrying a roller 33, moving on the side wall of the box or a suitable track during 55 the travel of the pushers through boxes. The shafts at the forward end of boxes 27 are provided on their lower ends with bevel-gears 34, meshing with similar gears 35 on short shafts 36, mounted in suitable bearings below shafts 60 28 and driven by sprocket-chains 37, passing around sprockets 38 carried thereby, and sprockets 39, formed on hubs 40, loose on a shaft 41, mounted upon the base 1 and locked to or released from said shaft by suitable 65 clutches 42. Said shaft 41 carries a worm-gear 43, meshing with a similar gear 43' upon a shaft 44, mounted on the under side of the base 1 and driven by a belt 45 from the power-shaft 3.

70 Boxes 26 are each provided adjacent to the discharge ends of boxes 27 with a pair of feed-rolls 46, disposed at the top and bottom thereof and extending transversely. The upper roll of each pair is arranged by any 75 suitable structure to yield upwardly against the pressure of springs 47. The shafts of the rolls of each pair carry sprockets 48, around which sprocket-chains 49 pass, and the shafts of the lower rolls are provided with sprockets 100 50, connected by sprocket-chains 51 with sprockets 52 on hubs 40.

Pivots mounted on arms depending from the tracks 25 or other convenient part are bell-crank levers 53, one being arranged 105 adjacent to the under side of each of the boxes 26 27. The short arm of each lever is pivotally connected with the adjacent box by a link 54, while the long arm carries a weight 55, which may be adjusted thereon. One of the shafts 28 of each pair is mounted 110 in suitable adjustable bearings, whereby any slack may be removed from chains 30.

115 The operation of my improved feed mechanism is as follows: Blocks of wood from which the excelsior is to be made are dropped into box 27, the top being open for this purpose, and are fed forward in said box by the pushers, which swing thereinto in pairs in the rear of the block or series of blocks. These 120 pushers are held firmly in engagement with the block during their travel through the box by said rollers 33, moving upon the side walls of the box or track, and when the block has been carried far enough to be engaged 125 by the rolls 46 the limit of travel of said pushers has been reached, and they swing out of the box through the openings in the sides

thereof. When these openings are reached, the rollers 33 run off the wall of the box or track provided therefor, permitting the pushers to swing upon their pivots by pressure thereof against the block, and thus gradually disengage the latter, so that the movement of the carrier-chains is not checked or stopped and there is no jamming or breaking of the parts which would occur were the 5 pushers not connected with the carrier-chains, so as to provide for such swinging movement thereof. The blocks are then engaged by the feed-rolls 46 and fed forward to the scorers and cutters. By providing 10 the clutch mechanisms described either one or both of the feed mechanisms may be thrown out of gear. Should there be a resistance or pressure upon the block operated on by the scorers and cutters sufficient to 15 overcome the action of weight 55, attached to box 26, said box will slide rearwardly, and should this pressure still continue said box will, by engagement with box 27, cause said box to move rearwardly, the two boxes then 20 moving together and against the combined action of both weights 55. Should any considerable resistance be encountered by the blocks at their entrance into the box 26 and engagement by the feed-rolls, box 27 will 25 yield rearwardly in a like manner. As soon as the pressure is removed the weights will restore said boxes to their normal positions. The forward end of the base of the machine carrying the feed mechanism is contracted, 30 so as not to obstruct the dropping of the excelsior from the cutters, the machine in use being elevated, so that the shavings can drop therebelow to any suitable receptacle for collecting the same.

40 I do not limit my invention to any particular number of scoring and cutting mechanisms and feed mechanisms therefor, but have found that a machine constructed as shown and described has a large capacity and is capable of being operated with a small amount of power.

Having thus fully described my invention, what I claim as new, and desire to secure by Letters Patent of the United States, is—

50 1. In a machine for cutting excelsior, a cutter and a scorer carried by independently-mounted carriers, means for causing said cutter and scorer to move in the same straight line during a portion of the movement of the carriers, the scorer in advance of the cutter, and means for feeding a block of wood to position to be acted upon by the cutter and scorer.

60 2. In a machine for cutting excelsior, a rotary carrier, a cutter carried thereby, a carrier arranged adjacent to said rotary carrier and having its axis of movement at right angles to the axis of rotation of the rotary carrier, a scorer carried thereby, means for causing said scorer to move into and out of the

plane of the cutter, and move therein during a portion of the movement of its carrier, in advance of the cutter, and means for feeding a block of wood to position to be acted on by the cutter and scorer.

70 3. In a machine for cutting excelsior, a rotary carrier, a cutter carried thereby, a scorer, a carrier for said scorer positioned adjacent to and mounted independent of said rotary carrier and constructed and arranged to swing said scorer into the plane of travel of the cutter in advance of the latter and to cause said scorer to move in the same straight line as the cutter and to swing said scorer out of the plane of travel of the cutter 80 after the completion of said straight-line movement, and means for feeding a block of wood in position to be acted upon by said cutter and scorer.

85 4. In a machine for cutting excelsior, a rotary carrier, a cutter having its cutting edge upon the one side of the carrier, a scorer, a carrier for said scorer positioned on the opposite side of said rotary carrier, and constructed and arranged to bring said scorer 90 into position upon the side of the rotary carrier carrying the cutting edge of the cutter and in advance thereof, and to impart a straight-line movement thereto, and remove the same therefrom after the completion of 95 the straight-line movement, and means for feeding a block of wood to position to be acted upon by said cutter and scorer.

100 5. In a machine for cutting excelsior, a rotary carrier, a cutter having its cutting edge projecting from one side of said carrier, said carrier having an opening formed therein in advance of the cutter, a scorer, a carrier for said scorer positioned upon the opposite side of the rotary carrier, and arranged to move 105 said scorer into and out of said opening, means for causing said carriers to move in unison while the scorer is in said opening and means for feeding a block of wood to position to be acted upon by said scorer and cutter.

110 6. In a machine for cutting excelsior, a rotary disk, a cutter carried thereby having its cutting edge upon one side thereof, said disk formed with an opening therethrough in advance of the cutter, a scorer, a carrier for said 115 scorer positioned on the opposite side of the scorer, and arranged to move said scorer into and out of the opening, means for causing the carriers to move in unison, while the scorer is in said opening, and means for feeding a block of wood to position to be acted upon by said scorer and cutter.

120 7. In a machine for cutting excelsior, a cutter, a carrier therefor, a scorer arranged at the rear of the cutter and its carrier, a carrier 125 for said scorer mounted independently of said cutter-carrier arranged to move said scorer into and out of the plane of travel of the cutter in advance thereof, and cause the same to move in the same straight line as the 130

- cutter, and a feed mechanism arranged at the front side of the cutter and its carrier for feeding a block of wood to position to be acted upon by said cutter and scorer.
- 5 8. In a machine for cutting excelsior, a carrier consisting of an endless chain or belt, a scorer carried thereby, a track arranged adjacent to said carrier, a roller carried by the scorer moving upon the one side of the track, 10 a yieldingly-mounted roller carried by the scorer moving upon the opposite side of the track, and means for imparting movement to said carrier.
- 15 9. In a machine for cutting excelsior, the combination with a cutter, of two independently-slidable feed boxes or ways arranged in such relative position that when the forward box has moved rearwardly a certain distance it will effect the rearward movement of the 20 rear box and the two will move together, means for offering a resistance to the rearward movement of each box, and feeding devices operating in said box.
- 25 10. In a machine for cutting excelsior, a rotary carrier, a cutter carried thereby, a carrier positioned adjacent to said rotary carrier comprising an endless belt or chain arranged to move the scorer carried thereby into and out of the plane of the cutter and
- to cause the same to move therein during a 30 portion of its movement in advance of the cutter, a scorer carried by said endless belt or chain, and means for feeding a block of wood to position to be acted upon by said cutter and scorer.
- 35 11. In a machine for cutting excelsior, a rotary carrier, a cutter having its cutting edge upon one side of the carrier, a scorer, a carrier for said scorer positioned on the opposite side of said rotary carrier, said scorer-carrier 40 comprising an endless belt or chain constructed and arranged to bring said scorer into position upon the side of the rotary carrier carrying the cutting edge of the cutter and in advance thereof, and to impart a 45 straight-line movement thereto, and remove the same therefrom after the completion of the straight-line movement, and means for feeding a block of wood to position to be acted upon by said cutter and scorer.
- 50 In testimony whereof I have signed my name to this specification in the presence of two subscribing witnesses.
